UNITED STATES PATENT OFFICE.

HARRY M. BLAETZ, OF PHILADELPHIA, PENNSYLVANIA, ASSIGNOR TO ROYAL ELECTROTYPE COMPANY, OF PHILADELPHIA, PENNSYLVANIA, A CORPORATION OF PENNSYLVANIA.

METHOD OF BACKING ELECTROTYPE PLATES.

Application filed November 7, 1924. Serial No. 748,428.

My invention relates to backing electrotype plates by pouring molten backing metal upon the tinned backs of the plates.

The purpose of my invention is to provide a process and a machine for obtaining a backing free from air-holes and of homogeneous density and shrinkage throughout.

A further purpose is to greatly reduce danger of failure of plates in the printing press by reason of hidden blow holes, and to reduce the thickness required initially for the backing because less shaving need be done in the final finishing operation.

A further purpose is to greatly straighten the plate, take out the wrinkles and level its surface, and generally to reduce the hand finishing which is required.

A further purpose is to strengthen and toughen the material of the plate and particularly that part closest to the electrotype.

A further purpose is to secure the greatest accuracy of registration of different electrotype plates from the same original plate by the faithfulness with which each copy is made to agree with the original.

A further purpose is to drive out particles of air from between the tinned electrotype and the backing by striking the bottom of the pan in which the electrotype lies progressively while the backing is still molten.

A further purpose is to make the progressive blows more effective by having them cushioned or "dead".

A further purpose is to strike blows progressively over the bottom of the pan and at the same time to press a grid upon the top of the backing.

A further purpose is to press a grid resiliently into the backing while the latter is still molten or nearly molten to prevent substantial creeping of the metal during its period of most rapid shrinkage, during solidification and during cooling from near its point of solidification.

A further purpose is to provide an inexpensive machine adapted to carry out my process.

Further purposes will appear in the specification and in the claims. 50

I prefer to illustrate my invention by several varieties only of a single form, selecting one which well illustrates the principles of my invention. 55

Figure 1 is a top plan view of a form of structure capable of carrying out my invention.

Figure 2 is a section upon line 2—2 of Figure 1. 60

Figure 3 is a section upon line 3—3 of Figure 2.

Figure 4 is a fragmentary side elevation of a grid seen in Figures 1, 2 and 3.

Figure 5 is a fragmentary bottom plan view of the grid of Figure 4. 65

Figure 6 is a fragmentary top plan view of a tray seen in Figures 1, 2 and 3.

Figure 7 is a fragmentary section upon line 7—7 of Figure 6. 70

Figure 8 is a fragmentary top plan view of the structure beneath the tray in Figure 3.

Figure 9 is a section corresponding generally with Figure 2 but showing a modification of the resetting devices. 75

Figure 10 is a section of Figure 9 upon line 10—10.

Figures 11 and 12 are fragmentary sections corresponding with Figure 9 but showing the parts in different positions. 80

Figures 13 and 14 are fragmentary top plan views and side elevations showing a modification of the grid holding structure, pouring and evolving mechanism appearing 85 in Figure 14.

Figure 15 is a top plan view of a plate backing equipment with which my invention may be advantageously associated.

Figure 16 is a side elevation of the structure seen in Figure 15. 90

Figure 17 is a section upon line 17—17 of Figure 15.

In all drawings like numerals refer to like parts. 95

Describing in illustration and not in limitation and referring to the drawings:—

When the lead has been poured upon the

tinned backs of electrotype plates, in the best process of backing plates now known to me and later herein described in connection with Figures 15-17, many of the plates are rendered soft in spots by blow holes.

These differ greatly in size but are ordinarily made up of a large number of very fine holes, making the plate spongy and hence unfit to support the pressure to which the plate is ultimately to be subjected. There is trouble also from the contraction of the backing parallel to its surface, which tends to compress and distort the image upon the faces of the electrotype, injuring the individual plates and interfering with proper registration in sets of plates intended for color printing.

If the blow hole fault be detected in time and it be not too serious, it can be corrected during the finishing operations but at considerable expense of time and skill and with a resultant inferior plate at best.

In spite of all care there are frequent discards at the press from air-holes sufficiently small not to be found and corrected during the hammering and testing process and sufficiently large to permit yielding under the great pressure of the press. There is also trouble, first apparent at the press, from lack of uniformity of density throughout the plate due to creeping of the metal while solidifying and cooling from the molten state.

I have discovered that the lack of uniform density due to blow holes within the plate may be avoided by progressively hammering the bottoms of the pans while the metal is still molten to cause the air there trapped to pass up through the molten metal or along the lower surface of the metal to the edge of the plate, securing greater strength and toughness and a very much more level surface and that at the same time creeping of the metal during solidification and consequent distortion of the plate and undue shrinkage of the plate may be stopped by resiliently pressing a grid of supporting metal against the upper surface of the metal while it is still molten and maintaining this pressure during the cooling process. Even a greatly curved electrotype can be straightened and flattened by my process.

In the first form of my invention I have illustrated a simple construction for rapping a tinned plate which has been covered with a molten backing 20 in a tray 21 specially intended for use within a rapping machine. The tray is rested upon any suitable supporting frame 22 of the machine and a thrust-receiving holder 23 is rested upon the top of the molten metal, being pressed upon the surface of the metal by

springs 24 held down by a top frame 25. The pressure is exerted through a set screw 26 locked in height adjustably by a nut 26'. The set screw is depressed by a lever arm 27 pivoted at 28 and latched, during the rapping operation beneath hook 29. The holder or cover 23 with its springs and adjustment is preferably removable in its entirety to give ready access to the tray.

The grid is provided with a roughened face 30 (Figures 4 and 5) to engage sufficiently with the surface of the molten metal to restrain the contraction of the metal during that portion of its cooling when the rate of contraction is greatest and the cohesion of the metal least; namely, during the earlier stages of solidification and during the relatively high contraction which ordinarily takes place in the upper range of temperature just below the congealing temperature.

I find that by such roughening I can greatly reduce and well equalize the contraction so as to relieve necessary contraction wholly from its objectionable features. The exact character of the roughening of what I term the "grid face" is not material provided it will interlock sufficiently to hold against strain parallel to the face in search directions. I illustrate projections 31 in rectangular arrangement so that they hold against creeping both lengthwise and across the plate. The projections are exaggerated in the illustration.

The tray, best seen in Figures 6 and 7, is provided with flanges 33 which position it with respect to the frame member 34, and with handles 35 by which it may be removed.

In order to drive out trapped air from beneath the molten metal, I tap the tray at the bottom so as to transmit the blows to the face of the electrotype which is being backed, finding advantage not only in the tapping itself but in a progressive advance of the tapping from the center toward the edges or, because of its greater convenience from one side or end toward the other.

The inconvenience of tapping the tray immediately after the molten backing has been poured makes it desirable ordinarily to tap the tray just before the metal solidifies and I illustrate this.

The tapping mechanism shown in Figures 1-3 comprises a plurality of plungers 36 which operate through a guide or guides 37 to move in a vertical direction and which are thrown upwardly by springs 38 resting against a support 39 carried by the frame of the rapping machine.

The plunger rods 40 are guided in support 39 and at their lower ends are screwed into bars 41 and locked therein by nuts 42.

Each bar may control any predetermined number and arrangement of plungers to rap

thus "cover" a particular section of the bottom of the tray of regular or irregular shape, so that the progress of the succession of rappings may follow the law determined upon. In the present case the plungers which operate together are arranged in rows across the tray in order to cover or rap a portion of the length of the tray with progression successively to other portions of the length of the tray, each of which is rapped by a different set or row of plungers.

I prefer to use a separate spring about each plunger rod rather than to reduce the number of springs and increase their strength. Each "bar" 41, whatever the shape or section of the bottom of the tray to be rapped by its plunger rods, is separately drawn downwardly slowly and quickly released. In my preferred form this is accomplished by face cams 43, engaging and drawing down pins 44 connected with the bars. The face cams are provided with cam surfaces 45 and the pins are supported from the bars by rods 46. Obviously the cams 43 can be identical and can be timed to any preferred order, beginning at either end or between the ends, according to the angular placing of the cams upon shaft 47 in bearings 48. In the form as illustrated the right hand cam of Figure 2 will engage first and therefore will release first and the cams will engage successively from right to left, so that the succession of releases will rap progressively from right to left in this figure.

Since it is best to take up all of each blow in the tray the heads of the plungers desirably terminate in ends of fibre or other material 49 to deliver non-resilient blows.

The interval between successive blows may be made as short as desired by increasing the speed of the shaft whether operated by hand or by power, or by increasing the number of sets of plungers and the "hammers" which they provide. It may also be made uniform not only within the succession of the set but between the last one and the first of the next, giving not only uniform spacing of blows but also close approach to uniformity of torque in the driving mechanism.

The driving mechanism shown in Figures 2 and 3 comprises a handle 50, a stub shaft 51 and gears 52, 53 upon the stub shaft 47 respectively. In Figure 14 shaft 47 is connected through mitre gears 54 with a shaft 47' to change the angle of the driving shaft with respect to the cam shaft.

My invention would obviously be carried out in its broader aspects by the delivery of blows to the bottom of the tray even if not progressively advancing nor successive and in the latter cases even if by a single set of hammers only upon different parts of the tray bottom, either the set or the tray ad-

vancing. The broad features of the grid control of shrinkage likewise requires relative motion only between the grid and the metal, whichever be moved to secure sectional interlocking.

In the form shown in Figures 9-12, the bars 41 lie beneath the top piece of a frame 55 by which all of the bars can be drawn down together against the tension of their springs 38 and of the frame-resetting spring 75. The frame 55 is drawn down by a pedal lever 57, pivoted at 58. The pedal lever is connected by link 39 with a lever 60 pivoted at 61 and connected by a bolt 62 with the frame 55.

While the lever 57 is held down the bars 41 are all locked down by means of a plurality of concurrently movable hooks 63, 63', 63², 63³, 63⁴, 63⁵, having different extents of overhang at 64 so as to engage with the bars 41 to differing extents. The hooks 63-63⁵ are mounted so as to engage and release the bars with movement, here shown as horizontal, of a support 66 which operates in guides 67 and is moved by handle 68 upon rod 69. The rod is threaded at 70 to engage with the fixed thread 71 and is swivel-connected with the bar 65. The hooks are shown in Figure 11 in position ready for connection with the several bars, the position assumed when the pedal lever 57 has been depressed but when the hooks have not been brought into hooking position with respect to the bars 41. In Figure 12 the position of the parts is shown corresponding with latching of the bars in their lowered position. As will be seen, operation of the handle 68 to move the hooks to the right in Figure 12 will release one after another, depending upon the depth of engagement of the bars with the hook members, and this depth of engagement is least at the right and is progressive greater from right to left.

In Figures 13 and 14 the mechanism is substantially that of Figures 1-3, differing in using a stub shaft 47' and mitre gearing 54 along with a grid holding mechanism which does not require the spacing lengthwise of the machine which is required by the lever 27, producing a more compact machine than that of Figures 1-3 but suffering the disadvantage that the trays are not so easily accessible for removal as are the trays of Figures 1-3. Part of the plate-backing construction of Figures 15 and 16 is seen in Figure 14.

In the grid holding mechanism, the bar 25' carries a nut 72 within which is threaded screw 73 of hand wheel 74. The screw is swiveled at 75 in a supporting bar 76 so that the support 23' with the grids and springs may be lifted in their entirety by means of the hand wheel. With this construction separated grids are used to corre-

spond with separate trays and the trays are intended to be placed and removed laterally instead of being accessible for placing and removing vertically as in the form of Figures 1-3.

In Figures 15, 16 and 17 I have shown the rapping machine of Figures 1-3 but with two grids for separate trays. The machine is located outside of and for use in connection with a plate-backing machine in which two trays at a time are successively tinned, backed, cooled and discharged. The rapping machine is placed close to the position of the plates when they have been partially cooled but before they have solidified, giving opportunity for rapping them just before their discharge.

A very desirable layout for backing electroplates is shown in Figures 15-17.

20 The plates 77 are laid face down in pans 78 and these pans are placed on top of the hot bath 79 of molten metal. The backs of the plates are then coated with tinning flux and covered with one or more thin sheets of soft tinning solder as is well known.

The hot bath almost immediately melts the thin sheets of solder covering the backs of the plates and raises the plates to about the temperature of the molten backing metal.

30 After the backs are tinned the pans are lifted to the adjacent section of the turntable 80. This turntable has four sections, 81, 82, 83 and 84, which are adapted in the positions shown successively to occupy (1) a position where 81 is shown, adjacent to the bath 79, where it receives the trays of tinned plates, (2) a position where 82 is located under the spout 85 of the cupola 86 from which it receives molten backing metal and where it is partly cooled by a blast of air from an air pressure pipe 87, (3) the position of 83 at which the molten backs are further cooled by being subjected to a blast of air directed by another air pipe 88 and (4) a position at which the backed plates are removed from subsequent operations. The operations at these several positions take place concurrently.

50 The emptied sections are successively filled with tinned plates in position (1), are turned from that position to position (2) to receive the backing metal and a cooling blast, are turned to position (3) for further cooling and from there are turned to position (4) for withdrawal.

55 The double tray 21' is shifted in its entirety with the turntable sections to the point of rapping or discharge. The rapping is done preferably in a separate position as the use of a rapping machine to rap the bottom of the trays in situ would unduly complicate the backing machine unless the grid holding device be omitted.

Where the rapper is left in place to oper-

ate upon a turntable-supported tray I prefer to use a form of rapper in which all of the rapping hammers may be depressed at the same time or to relatively lift the rapper with respect to the tray after the latter has been turned or moved over the hammers.

65 Preferably as the plates come to position (3), just before solidification they may be transferred to my rapping machine for rapping with subsequent direct discharge from it or retransfer to position (4).

70 Whether the rapping machine be independent of the backing mechanism or cooperating therewith, whether it rap one plate or more at a time and whatever the law of the machine as to lateral movement of the plunger or plate or the succession of the rapper where more than one set of rappers is used, rapping or jarring of the under surface of the tray is effective to reduce the air bubbles and, as to those which are left, to 80 reduce their size.

75 In operation, the rapping not only drives the air along in bubbles to the side or end of the plate or causes it to escape through the body of molten metal to that portion of the back of the plate which will be cut off during the planing or shaping of the back of the plate, but there is also a combination between this feature and the roughening of 90 the back of the plate by the grid which facilitates release of the bubbles at the back of the plate. Those bubbles which do not wholly escape will lie within the raised portion of the metal left by the roughening.

85 The pressure from the grid upon the 100 molten metal increases the compression and therefore the pressure of any air which is trapped within the metal or between it and the electrotype, increasing the capacity of this air to flow during the rapping process 105 and reducing the size of air hole caused by any given quantity of trapped air.

95 A partial advantage of the rapping of the plate will be obtained, even where the air is not wholly expelled, if it be sufficiently 110 dissipated and distributed so that there is no concentration of even fine air bubbles to produce spongy or soft spots in the plate, as the same size of air holes which become quite objectionable in spongy spots in the 115 plate are not proportionally objectionable when they occur singly and spaced some distance from other corresponding bubbles.

100 It will be evident that the blows of the hammers must not be heavy enough nor sharp enough to injure the face of the electrotype, which rests against the bottom of the tray.

105 I recognize that my disclosure herein will suggest to those skilled in the art other ways 115 of securing all or a part of the benefit of my invention without copying the form shown and intend therefore to include herein all

such other forms, modifications and changes as come within the reasonable spirit and scope of my invention.

Having thus described my invention, what I claim as new and desire to secure by Letters Patent is:—

1. The method of distributing or eliminating air trapped between the back face of an electrotype and a molten backing therefor or within the backing, which consists in jarring the electrotype after the back has been applied and before it solidifies.

2. The method of distributing or eliminating air trapped between the back face of an electrotype and a molten backing therefor or within the backing, which consists in jarring the electrotype by impulses from the face side of the electrotype toward the backing.

3. The method of distributing or eliminating air trapped between the back face of an electrotype and a molten backing therefor or within the backing, which consists in jarring the electrotype by blows delivered from the face side of the electrotype and progressively spreading the area covered by the blows over the face of the electrotype.

4. The method of distributing or eliminating air trapped between the back face of an electrotype and a molten backing therefor or within the backing, which consists in progressively rapping the electrotype at spaced distances along its surface after the backing has been applied and before it solidifies.

5. The method of distributing or eliminating air trapped between the back face of an electrotype and a molten backing therefor or within the backing, which consists in progressively rapping the electrotype along its surface at a plurality of points at a time before the backing solidifies.

6. The method of distributing or eliminating air trapped between the back face of an electrotype and a molten backing therefor or within the backing, which consists in progressively rapping the electrotype along its surface at a plurality of points at a time covering zones progressively extended to cover substantially the entire surface of the electrotype.

7. The method of distributing or eliminating air trapped between the back face of an electrotype and a molten backing therefor or within the backing, which consists in placing the electrotype face down in a holder, preparing the plate for intimate union with the backing, applying molten backing to the back of the electrotype and striking the holder at a plurality of points at a time while moving the electrotype and striking means with respect to each other to progressively change the points at which the holder is struck.

8. The method of distributing or elimi-

nating air trapped between the back face of an electrotype and a molten backing therefor or within the backing, which consists in placing the electrotype face down in a holder, preparing the plate for intimate union with the backing, covering its back with molten backing metal and striking the holder deadened blows.

9. The method of distributing or eliminating air trapped between the back face of an electrotype and a molten backing therefor or within the backing by plungers resiliently pressed toward contact with a tray in which the electrotype is rested, which consists in turning the plate for intimate union with the backing, covering the back of the plate with molten metal, retracting the plungers slowly to intensify the pressure and releasing them suddenly to allow them to strike the bottom of the holder.

10. The method of preventing undue contraction of the molten backings of electrotypes during cooling of the same which consists in holding the backings during contractions by means interfitting with the metal at intervals to control movement parallel with the faces of the electrotype.

11. The method of preventing undue contraction of the molten backings of electrotypes during cooling of the same which consists in restraining movement of the congealing backing of the molten metal, effecting the restraint at intervals along the surface of the backing.

12. The method of preventing undue contraction of the molten backings of electrotypes during cooling of the same which consists in pressing against the back surface thereof a holding member having a smaller total contraction through the ranges of cooling represented than that of the backing metal.

13. The method of preventing undue contraction of the molten backings of electrotypes during cooling of the same which consists in holding the outer surface of the backing metal by a grid of solid material.

14. The method of preventing undue contraction of the molten backings of electrotypes during cooling of the same which consists in backing the electrotype within a holder of molten metal, frictionally engaging the top of the backing with considerable pressure and striking the face of the holder progressively with respect to the surface of the holder.

15. The method of relieving molten backing metal of trapped air which consists in impressing upon the back of the metal a grid of solid material and subsequently jarring the face of the electrotype by impulses from the face side thereof.

16. The method of backing electrotypes which consists in supplying the electrotype in a suitable holder with a molten backing

adapted to adhere to the back surface of the electrotype, restraining undue contraction of the upper part of the backing material and rapping the holder.

17. The method of backing electrotypes which consists in supplying the electrotype in a suitable holder with a molten backing

adapted to adhere to the back surface of the electrotype, restraining undue contraction of the upper part of the backing material and 10 rapping the holder progressively over its surface.

HARRY M. BLAETZ.
